(57) CLAIM

The ornamental design for a storage box, as shown and described.

DESCRIPTION

FIG. 1 is a perspective view of the storage box showing my new design;

FIG. 2 is a perspective view thereof from another angle; FIG. 3 is a perspective view thereof from another different angle;

FIG. 4 is a left side elevational view thereof;

FIG. 5 is a right side elevational view thereof;

FIG. 6 is a rear elevational view thereof;

FIG. 7 is a front elevational view thereof;

FIG. 8 is a top plan view thereof;

FIG. 9 is a bottom plan view thereof; and,

FIG. 10 is a perspective view thereof when the storage box is open.

The broken lines in the figures show portions of the storage box which form no part of the claimed design.

1 Claim, 10 Drawing Sheets
